DESIGN FOR A SHOE

Vincent De Liso, Astoria, N. Y., assignor to Saks and Company, Inc., New York, N. Y., a corporation of New York

Application January 29, 1934, Serial No. 50,548

Term of patent 3½ years

To all whom it may concern:

Be it known that I, VINCENT DE LISO, a citizen of the United States, residing in Astoria, Long Island, N. Y., have invented a new, original, and ornamental Design for a Shoe, of which the following is a specification, reference being had to the accompanying drawing, forming part thereof.

Fig. 1 is a plan view of a shoe showing my new design.

Fig. 2 is a side elevation of the shoe.

I claim:

The ornamental design for a shoe, as shown.

VINCENT DE LISO.
